Primary Examiner — Zenia I Bennett(74) *Attorney, Agent, or Firm* — Tope-McKay & Associates(57) **CLAIM**

The ornamental design for a lice removal device, as shown.

DESCRIPTION

FIG. 1 is a first front top perspective view of a lice removal device in accordance with the new design;

FIG. 2 is a second front top perspective view thereof;

FIG. 3 is a front bottom perspective view thereof;

FIG. 4 is a top elevation view thereof;

FIG. 5 is a bottom elevation view thereof;

FIG. 6 is a left side elevation view thereof;

FIG. 7 is a right side elevation view thereof;

FIG. 8 is a rear elevation view thereof; and,

FIG. 9 is a front elevation view thereof.

The broken lines in the drawing depicting portions of the bottom of the lice removal device are for illustrative purposes only and form no part of the claimed design.
